UNITED STATES PATENT OFFICE.

JOHN W. HOUGH, OF FAIRBANK, IOWA.

FENCE-POST.

1,033,322.

Specification of Letters Patent.

Patented July 23, 1912.

Application filed September 16, 1911. Serial No. 649,600.

To all whom it may concern:

Be it known that I, JOHN W. HOUGH, a citizen of the United States of America, residing at Fairbank, in the county of Bu-
5 chanan and State of Iowa, have invented new and useful Improvements in Fence-
Posts, of which the following is a specification.

This invention relates to improvements in
10 fence posts, and aims to provide an im-
proved and novel form of fence post em-
bodying a reinforced plastic mass.

The invention contemplates a fence post
15 of the above character, the reinforcing means
of which shall provide a lightning arrester
whereby the same may be grounded thereby
eliminating this menace to live stock, par-
ticularly when the post is used in fence
structures.

20 The invention consists of a post con-
structed of cement, or like self-setting plastic
material, a metallic stay or reinforcing mem-
ber embedded in the post centrally thereof,
25 and plates arranged upon the post and re-
ceiving binding wires whereby a self-con-
tained and unitary structure is provided, the
said plates also serving to retain the fence
wires in position.

With the above and other objects in view
30 the invention consists in the construction,
combination, and arrangement of parts here-
inafter fully described, claimed, and illus-
trated in the accompanying drawings, where-
in—

35 Figure 1 is a perspective view of the
fence post embodying the invention. Fig. 2
is a vertical sectional view through the post.
Fig. 3 is a perspective view of the reinforce-
40 ing means showing the parts in their assem-
bled position. Fig. 4 is a top plan view
of one of the plates, and Fig. 5 is a per-
spective view of the same.

Referring to the accompanying drawings
45 in which like numerals of reference desig-
nate similar parts throughout the several
views, the numeral 1 designates the body of
the post, composed of cement, concrete or
other plastic material of a like nature. Ar-
50 ranged centrally of the body 1 and project-
ing above and below the same is a reinforce-
ing bar 2, the latter being, preferably,
squared in cross section and pointed at its
upper end. Positioned upon the reinforcing
55 bar 2 within the body 1, and spaced a suit-
able distance from each other, are a plurality

of securing plates 3 and a retaining plate 4.
The plates 3 are formed with lateral exten-
sions 5, which project through one side of
the body 1 and are stamped to provide hooks
6, the purpose of which will be hereinafter 60
fully described. Each of the plates 3 are
formed centrally with a squared opening 7,
which latter receives the reinforcing bar 2,
and with a plurality of marginal openings
8, the marginal openings of one plate alin- 65
ing with those of the other plates and receiv-
ing binding wires 9. The plate 4 is posi-
tioned upon the reinforcing bar 2 below the
plates 3 and is provided with marginal open-
ings 10, the plate 4 being wholly embedded 70
in the body 1 of the post.

The binding wires 9 have their upper ends
secured to the upper end of the bar 2, and
are preferably twisted thereabout for a por-
tion of their length. These wires are passed 75
through the openings 8 and 10 of the plates
3 and 4 respectively and at their lower ends
are secured to the bottom of the bar 2 where-
by the plates 3 and 4 are securely held in
position and the body 1 of the post more 80
securely reinforced. As before stated the
hooks 6 are stamped from the plates 3 and
the openings formed by the stamping of said
hooks are adapted to receive a retaining rod
11, which latter engages the bills of the 85
hooks 6, in the application of the rod to the
plates whereby the fence wire which is en-
gaged by the hooks 6 is securely held in posi-
tion. At its upper end the rod 11 is formed
with a hooked terminal for engagement with 90
the hook 6 of the upper plate 3 so that the
rod may be supported in the assembling of
the parts, the lower end of the rod being
bent upon or otherwise secured to the under
surface of the lowermost of the plates 3. 95

From the above description taken in con-
nection with the accompanying drawings it
will be seen that a post constructed in ac-
cordance with the present invention forms
a complete metallic circuit from the fence 100
wire to the ground thereby forming a light-
ning arrester for the protection of stock.

Having thus described my invention, what
I claim and desire to secure by Letters-Pat-
ent, is:

A fence post comprising a plastic body, a
reinforcing rod embedded in said body,
spaced securing plates mounted upon the
said rod and provided with alining open-
ings, binding wires secured to said rod above 110

and below said plates and passing through the openings therein to securely hold the plates to the rod and reinforce the post, said plates being provided with lateral extensions projecting through the body, hooks stamped from said extensions, and a retaining rod adapted to be positioned within the openings formed in the stamping of the

hooks, said rod coöoperating with the hooks to secure the wires of the fence in the hook. 10

In testimony whereof I affix my signature in presence of two witnesses.

JOHN W. HOUGH.

Witnesses:

W. L. MURPHY,
C. B. EVERETT.
